AWNING STRUCTURE

Edgar S. Waddell, Cincinnati, Ohio, assignor to
 The Randall Company, Cincinnati, Ohio, a
 corporation of Ohio

Application September 15, 1936, Serial No. 100,903

11 Claims. (Cl. 156—43)

This invention relates to an awning structure of the type which includes a canopy applicable to a window or door aperture in position to overhang the aperture.

An object of the invention is to provide a greatly simplified and unusually inexpensive awning structure, which may be installed, dismantled for storage, repairs, or replacement, and manipulated in a most convenient and facile manner.

Another object of the invention is to provide an awning structure having the above mentioned advantages, which is capable of accommodating window or door apertures of various widths, and employing the simplest possible means for the purpose.

Another object of the invention is to provide a ventilated awning structure of the character stated, wherein movement of the fabric portion thereof to a collapsed or folded inoperative position results in disposition of the fabric portion to a protected and concealed location entirely within the confines of the canopy portion of the awning structure.

The foregoing and other objects are attained by the means described herein and disclosed in the accompanying drawing, in which:

Fig. 1 is a fragmental perspective view of an awning structure embodying the invention, and showing its application to the frame of a window or door aperture.

Fig. 2 is a fragmental cross sectional view taken on line 2—2 of Fig. 1.

In the accompanying drawing, the frame of a door or window aperture is indicated by the characters 4, 5 and 6, the members 4 and 6 being the uprights, and the member 5 being the horizontal upper connecting piece for the uprights.

To the horizontal member 5 there is fastened, by any suitable means such as screws, nails, or the like 3 a canopy indicated generally by the character 7. The canopy preferably is in two or more parts numbered 8 and 9, adapted to telescope or overlap one another for the purpose of altering the length of the canopy to accommodate frames of various sizes. Each section of the canopy preferably is provided with a series of louvres or ventilators 10 which serve as ports for the escape of heat or room odors that might be pocketed within the canopy in the absence of such ports. The outer end of each canopy section is provided with an angular side member 12, preferably integral with the associated canopy section, and bent substantially at right angles so as to meet an upright member of the aperture frame 55 along an edge 13 of the canopy side piece.

The upper edge of each canopy section is provided with a mounting flange 14 bent at an angle to the front face of the canopy so as to flatly abut the upper member 5 of the aperture frame. The lower forward edge of the canopy, or each section thereof, is provided with a downwardly and inwardly turned flange 15, the flanges 15 of each canopy section being adapted to overlap as at 16 in substantially the manner that the mounting flanges 14 of each section overlap at 17. As will be understood, adjustment in the length of the canopy may be effected by sliding the sections 8 and 9 longitudinally, before application of the fastening means 18 which is common to both sections. The mounting flange 14 of one of the canopy sections may be pierced or apertured at a proper location to accommodate the fastener 18 after determining the amount of overlap necessary to accommodate the canopy to a given size of frame.

The character 19 indicates a brace which may be in the form of a metal strip spot welded or otherwise fixed to the under face of the canopy section 8, and having a downwardly turned end 20 in the plane of the mounting flange 14, whereby the brace may be screwed or otherwise attached to the aperture frame, if necessary or desirable. As will be understood, the brace may be dispensed with on canopies which are not of unusual length, that is, the brace is not absolutely essential to the combination, as the overlap of the flanges 15 of sections 8 and 9 are turned at such an angle as to preclude lateral separation of the sections in the region of the overlap.

The characters 21 and 22 indicate, respectively, front and side awning sheets, preferably of an accepted fabric material, adapted to be supported at their upper edges 23 and 24, respectively, upon the awning canopy. The lower edges 25 and 26 are suitably secured, in accordance with common practice, to a U-shaped metallic frame 27 having legs that extend from the forward portion of the awning to pivots 29 located upon the uprights of the aperture frame. By the use of means including a rope or the like 30, the frame 27 may be swung about its opposed pivots 29 to a position underneath and within the confines of the canopy 7. It is deemed unnecessary to disclose specifically the arrangement of ropes and pulleys commonly used for collapsing and extending the awning, as any acceptable and well known type of means for that purpose may be employed. The character 31 indicates a fastener or spool to which the rope 30 may be fastened for holding the awning in the collapsed position.

The upper edges of the fabric sheets 21 and 22 are associated with the canopy in an exceedingly simple and novel manner whereby, upon disposing the fabric material to the collapsed awning position, the material assumes a protected position well within the confines of the canopy. The means of associating the upper edges of the fabric sheets with the canopy are so designed as to permit easy detachment in the event that it is necessary to remove the sheet material for repairs, replacements, or winter storage, while at the same time resisting accidental displacement or detachment as the awning is manipulated to extend it or collapse it, as desired.

Referring to Fig. 2 of the accompanying drawing, the character 32 indicates an awning fabric support, a plurality of which are employed, the number thereof depending upon the length of the canopy. Each awning fabric support is preferably in the form of a hook having a securing base portion 33 welded or otherwise fixed to the under face of the canopy at a location near the forward flange 15. The support has an elongated shank portion 34 which extends in spaced substantial parallelism with the inclined top of the canopy, which shank portion is unusually long so as to provide a guide for the sliding of the awning grommets 35 from the forward position shown in Fig. 2, to a shifted position at or near the free end 36 of the hook. As the shank of the awning support or hook is quite long, the free curved end 36 thereof terminates comparatively close to the upper securing flange 14 of the canopy. The curved end 36 of the awning support 32 is bent toward the under face of the canopy top and rests thereon in substantial contact at the location 37. The awning support or hook 32, being resilient, resists accidental displacement of the grommet from the shank 34 when the awning is disposed to the collapsed condition, although deliberate displacement of the grommet upwardly along the shank and off the free curved end, is a matter of easy manipulation.

The triangular side pieces 12 of the canopy are provided with awning fabric support means 39 similar to those indicated at 32, so that fabric side pieces 22 may just as easily be detached from the canopy when it is desired to remove the fabric portion of the awning for winter storage, or for other purposes.

The operation of the device is as follows:

Assuming that the awning structure of Fig. 1 is initially in the extended or operative position and that it is to be disposed in the collapsed or inoperative position, the operator may manipulate the rope 38 or equivalent means for moving the U-shaped frame 21 upwardly about its pivots 29 to shift the transverse member 40 to a position beneath the canopy and beyond the forward flange 15 thereof. In so shifting the frame, the fabric of the awning will, as heretofore, be compacted in a multiple of folds as it is swung upwardly, and upon entry of the folded mass into the protective confines of the canopy, the grommets 35 which are slidably supported upon the awning fabric supports 32, will be crowded toward the aperture frame and caused to slide upwardly and inwardly along the elongated shank portions of the supports. This shifting of the grommets results in their yielding ample space at the forward portion of the canopy for accommodating the awning sheet and permitting it to assume a position of retirement therein, at which position the fabric sheeting is effectually protected from the elements. By providing the

turned portion 36 on each of the awning fabric supports 32, the grommets are prevented from sliding off the free ends of the awning supports when shifted rearwardly as above explained; however, when it is desired to deliberately release the grommets from the supports 32, that may be accomplished quickly and simply by the mere act of forcing them past the contact points 37. The grommets 41 of the awning side pieces 22, may in a like manner be disassociated from the awning supports 39, which are similar to those indicated at 32 of Fig. 2. The side members 12 of the canopy may advantageously be provided with integral inwardly turned perforate lugs 43, adapted to receive screws or other fastening means for securing the side pieces of the canopy to the aperture frame. In its preferred form, the entire canopy is constructed cheaply and quickly from sheet metal subjected to a punch press operation. It is anticipated that the production of unusually long canopies may require the interposition of a separate connecting member independent of the canopy sections 8 and 9, and cooperating therewith in substantially the manner set forth in the patent of Voorhees No. 798,756. Details such as this, however, are secondary to the provision of the means herein disclosed for shifting of the grommets along a stationary support, from which support the grommets may easily be displaced for dismantling the awning structure.

Attention is directed to the fact that the angularity between the flange 15 and the exposed face of the canopy, is less than a right angle, so that the flanges 15 of the adjacent canopy section 35 have a locking relation with one another after the assembly is installed. It is to be understood that other types of interlocking means may be provided, if desired, and that various other modifications and changes in the structural details of the device may be made, within the scope of the appended claims, without departing from the spirit of the invention.

What is claimed is:

1. In an awning structure which includes a ventilated canopy extensible in the direction of its length for accommodating aperture frames of various widths, the combination of a sheet of flexible awning material and a supporting frame therefor movable to a collapsed awning position at which the sheet of awning material enters beneath the canopy for protection from the elements, said canopy including a series of awning sheet supports in the form of hooks having elongated shank portions extending between the forward portion and the rear portion of the canopy, and upon which the upper portion of said sheet may slidably shift, to yield space at the forward portion of the canopy, for accommodating the awning sheet beneath the canopy when collapsed.

2. An awning structure which comprises in combination, a canopy to be secured over a door or window aperture, an awning sheet having upper and lower edges, a supporting frame for the lower edge of the awning sheet arranged for movement to and from a collapsed awning position beneath said canopy, means along the upper edge of the awning sheet for suspending said sheet, and cooperative suspending means on the canopy comprising a series of awning sheet supports in the form of elongated hooks each having an extensive shank portion disposed substantially along the width of the canopy and along which the means on the upper edge of the awning sheet may slide to a position of re-

irement well within the confines of the canopy, to make room for the awning sheet material when the awning is collapsed.

3. An awning structure which comprises in combination, a canopy to be secured over a door or window aperture, an awning sheet having upper and lower edges, a supporting frame for the lower edge of the awning sheet arranged for movement to and from a collapsed awning position beneath said canopy, means along the upper edge of the awning sheet for suspending said sheet, and cooperative suspending means on the canopy comprising a series of awning sheet supports in the form of elongated hooks each having an extensive shank portion along which the means on the upper edge of the awning sheet may slide to a position of retirement well within the confines of the canopy, to make room for the awning sheet material when the awning is collapsed, said hooks each having a base end fixed to the canopy and a yielding free end above the base end, over which free end the first mentioned suspending means may be slid for quick detachability of the awning sheet from the canopy.

4. An awning structure which comprises in combination, a canopy to be secured over a door or window aperture, an awning sheet having upper and lower edges, a supporting frame for the lower edge of the awning sheet arranged for movement to and from a collapsed awning position beneath said canopy, means along the upper edge of the awning sheet for suspending said sheet, and cooperative suspending means on the canopy comprising a series of awning sheet supports in the form of elongated hooks each having an extensive shank portion along which the means on the upper edge of the awning sheet may slide to a position of retirement well within the confines of the canopy, to make room for the awning sheet material when the awning is collapsed, said hooks each having a base end fixed to the canopy and a yielding free end above the base end, over which free end the first mentioned suspending means may be slid for quick detachability of the awning sheet from the canopy, said free end being normally in yielding contact with the canopy to preclude accidental displacement of the awning sheet relative to the canopy.

5. An awning structure which comprises in combination, a canopy to be secured over a door or window aperture, an awning sheet having upper and lower edges, a supporting frame for the lower edge of the awning sheet arranged for movement to and from a collapsed awning position beneath said canopy, means along the upper edge of the awning sheet for suspending said sheet, and cooperative suspending means on the canopy comprising a series of awning sheet supports in the form of elongated hooks each having an extensive shank portion along which the means on the upper edge of the awning sheet may slide to a position of retirement well within the confines of the canopy, to make room for the awning sheet material when the awning is collapsed, said hooks each having a base end fixed to the canopy and a yielding free end above the base end, over which free end the first mentioned suspending means may be slid for quick detachability of the awning sheet from the canopy, said free end being normally in yielding contact with the canopy to preclude accidental displacement of the awning sheet relative to the canopy, while the adjacent extensive shank por-

tion rests in spaced substantial parallelism with the top of the canopy.

6. An awning canopy for supporting the upper edge of a fabric awning sheet, and comprising in combination a pair of complementary loured sections each comprising an inclined top portion with a mounting flange along one edge and a guide flange along an opposed edge thereof, said guide flanges each being turned inwardly toward the canopy interior at an angle less than a right angle, whereby upon placing the sections in overlapping relationship, with the mounting flanges fastened to a support, the guide flanges lock with one another to preclude lateral separation of the canopy sections, and awning fabric support means within the canopy comprising a series of hook-like members each having a base part fixed to a section near the guide flange thereof, and an elongated shank portion extended from the base part to a location near said mounting flange.

7. An awning canopy for supporting the upper edge of a fabric awning sheet, and comprising in combination a pair of complementary loured sections each comprising an inclined top portion with a mounting flange along one edge and a guide flange along an opposed edge thereof, said guide flanges each being turned inwardly toward the canopy interior at an angle less than a right angle, whereby upon placing the sections in overlapping relationship, with the mounting flanges fastened to a support, the guide flanges lock with one another to preclude lateral separation of the canopy sections, and awning fabric support means within the canopy comprising a series of hook-like members each having a base part fixed to a section near the guide flange thereof, and an elongated shank portion extended from the base part to a location near said mounting flange, said elongated shank portion having a free end adapted to receive or release an awning sheet edge held in suspension by the shank portion of the hook-like member.

8. An awning canopy for supporting the upper edge of a fabric awning sheet, and comprising in combination a pair of complementary loured sections each comprising an inclined top portion with a mounting flange along one edge and a guide flange along an opposed edge thereof, said guide flanges each being turned inwardly toward the canopy interior at an angle less than a right angle, whereby upon placing the sections in overlapping relationship, with the mounting flanges fastened to a support, the guide flanges lock with one another to preclude lateral separation of the canopy sections, and awning fabric support means within the canopy comprising a series of hook-like members each having a base part fixed to a section near the guide flange thereof, and an elongated shank portion extended from the base part to a location near said mounting flange, said elongated shank portion being spaced from the canopy and having a free end in yielding contact upon the canopy, at said location.

9. A canopy for supporting the upper edge of a fabric awning sheet which is furnished with grommets along said edge, the canopy comprising an inclined top portion having an upper edge and a lower edge, the lower edge being the forwardly extended edge of the canopy, and interior elongated support means fixedly mounted relative to the canopy and adapted to receive the grommets of the awning sheet and to guide said grommets inwardly and away from the lower edge of the

canopy top interiorly thereof when the awning sheet is collapsed and packed into the space beneath the canopy.

10. A canopy for supporting the upper edge of a fabric awning sheet, which latter includes suspension means along an upper edge thereof, the canopy comprising an inclined top portion having an upper edge and a lower edge, the lower edge being the forwardly extending edge of the canopy, and interior elongated support means fixedly mounted relative the canopy and adapted to support the suspension means of the awning sheet and to guide said suspension means inwardly and away from the lower edge of the canopy top interiorly thereof when the awning sheet is collapsed and packed into the space beneath the canopy.

11. In an awning structure which includes a canopy for over-hanging the aperture frames of doors and windows, the combination of a sheet of flexible awning material and a supporting frame therefor movable to a collapsed awning position at which the sheet of the awning material enters beneath the canopy for protection from the elements, said canopy including a series of awning sheet supports in the form of hooks having elongated shank portions extending between the forward portion and the rear portion of the canopy, and upon which the upper portion of said sheet may slidably shift, to yield space at the forward portion of the canopy for accommodating the awning sheet beneath the canopy when collapsed.
